[57] CLAIM

The ornamental design for a cover for the bed of a pickup truck, as shown and described.

DESCRIPTION

FIG. 1 is a perspective view of the top, rear and one side of a cover for the bed of a pickup truck showing my new design;

FIG. 2 is a top plan view thereof;

FIG. 3 is a rear elevation view thereof;

FIG. 4 is a side elevation view thereof, the opposite side being a mirror image of that shown;

FIG. 5 is a front elevation view thereof; and,

FIG. 6 is a bottom plan view thereof.

FIG. 1

FIG. 2

FIG. 3

FIG. 4

FIG. 5

FIG 6
